DESIGN FOR A TIRE

Chase F. Ofensend, Akron, Ohio, assignor to The
B. F. Goodrich Company, New York, N. Y., a
corporation of New York

Application January 21, 1949, Serial No. 343

Term of patent 14 years

(Cl. D90—20)

To all whom it may concern:

Be it known that I, Chase F. Ofensend, a citizen of the United States, residing at Akron, in the county of Summit and State of Ohio, have invented a new, original, and ornamental Design for a Tire, of which the following is a specification, reference being had to the accompanying drawing, forming a part thereof.

In the drawing, the figure is a perspective view of a tire embodying my new design.

I claim:

The ornamental design for a tire, as shown.
CHASE F. OFENSEND.
